(57) **CLAIM**

The ornamental design for a display stand and/or stand with display as shown and described.

DESCRIPTION

FIG. 1 is a top front isometric view of a display stand and/or stand with display showing the claimed design;

FIG. 2 is a bottom rear isometric view thereof;

FIG. 3 is a top rear isometric view thereof;

FIG. 4 is a rear elevation view thereof;

FIG. 5 is a front elevation view thereof;

FIG. 6 is a right side elevation view thereof;

FIG. 7 is a left side elevation view thereof;

FIG. 8 is a top plan view thereof;

FIG. 9 is a bottom plan view thereof;

FIG. 10 is a top front isometric view thereof showing the claimed design in an environment in which it may be used;

FIG. 11 is a top front isometric view of another embodiment of a display stand and/or stand with display showing the claimed design;

FIG. 12 is a bottom rear isometric view thereof;

FIG. 13 is a top rear isometric view thereof;

FIG. 14 is a rear elevation view thereof;

FIG. 15 is a front elevation view thereof;

FIG. 16 is a right side elevation view thereof;

FIG. 17 is a left side elevation view thereof;

FIG. 18 is a top plan view thereof;

FIG. 19 is a bottom plan view thereof; and,

FIG. 20 is a top front isometric view thereof showing the claimed design in an environment in which it may be used. The broken lines in the figures show portions of the display stand, stand with display, or environment that form no part of the claimed design.

1 Claim, 20 Drawing Sheets
